INVENTOR

W. S. Ayres

UNITED STATES PATENT OFFICE.

WALLACE S. AYRES, OF HAZLETON, PENNSYLVANIA.

HITCHING-STAPLE.

SPECIFICATION forming part of Letters Patent No. 628,911, dated July 18, 1899.

Application filed January 7, 1897. Serial No. 618,375. (No model.)

To all whom it may concern:

Be it known that I, WALLACE S. AYRES, a citizen of the United States, and a resident of Hazleton, in the county of Luzerne and State 5 of Pennsylvania, have invented a new and useful Hitching-Staple for Cars, of which the following is a specification.

My invention relates to improvements in hitching-staples for mine and other cars, 10 which are attached to a cross-beam at either end of the car; and the objects of my improvements are, first, to so construct the staple that all indirect pulls upon it, such as occur when the car passes from a level to an inclined plane 15 or when it passes over the summit of the plane, will not bend it; second, to use a minimum of metal in its construction; third, to so construct it that it will in no way interfere with the coupling and uncoupling of the cars, and, 20 fourth, to so make it that it may be applied without any alteration in the cars. I attain these objects by the mechanism illustrated in the accompanying drawings, in which—

Figure 1 is a rear end view of the hitching- 25 staple; Fig. 2, a side view showing the staple as attached to the cross-beam of car; Fig. 3, a front end view, and Fig. 4 a plan view of the entire hitching-staple removed from the cross-beam.

Similar letters refer to the same parts 30 through the several views.

The round part A A constitutes the main body of the hitching-staple. The nuts B B secure it to the cross-beam G G of the car. 35 It can also be secured to the beam by the use of slots and keys instead of nuts or by any of the devices now in common use. The wings C C are a part of the hitching-staple and are formed with the round body by drop-forging 40 and without any welding together of the parts. These wings can be made to touch the washer-plate D D at various points across its entire width, but are preferably provided with projections F F, so as to insure a perfect contact 45 with the washer-plate D D at its outer edge, thus enabling the staple to resist any bending action that may occur from an oblique pull up or down, and also to insure the nuts B B drawing the staple against the washer-plate

D D and beam G G in the firmest manner pos- 50 sible. The washer E is extended on either side of the hitching-staple and connects with the side beams of the car in the usual way by bolts. Economy of material is accomplished from the fact that the wings are made only 55 thick enough to resist the bending action for a given angle of oblique pull, while the body of the staple is made sufficiently large to resist the direct pull.

The wings C C are simply added to any old 60 form of staple and are so placed on each side of the center of the loop as to in no way interfere with the coupling and uncoupling of the cars. By thus adding these brace-wings C C to any old form of staple my invention can be 65 applied to any cars now in use without any alterations in the cars by simply removing the old form of staple.

I prefer to carry out the features of my invention as shown in the accompanying drawings, 70 although the wings can be modified in shape and location to suit different constructions of cars and different methods of fastening the staple to the cross-beam.

What I claim as my invention, and desire 75 to secure by Letters Patent, is—

1. A hitching-staple having one or more brace wings or projections for bracing the body of the staple, substantially as set forth.

2. A hitching-staple having one or more 80 brace wings or projections integral with the body of the staple, substantially as set forth.

3. A hitching-staple having brace wings integral with the staple and situated on opposite sides of each fork of the staple, substan- 85 tially as set forth.

4. A hitching-staple having wings C C pro- 90 vided with the projections F F, substantially as shown and described.

5. The combination of a hitching-staple, 95 having the wings C C and the projections F F, with the washer-plate D D and cross-beam G G, substantially as shown and for the purposes specified.

WALLACE S. AYRES.
